UNITED STATES PATENT OFFICE

154,157

DESIGN FOR A TILE FLOOR AND WALL COVERING

John E. Ryan, Danbury, Conn.

Application September 29, 1948, Serial No. 148,827

Term of patent 14 years

(Cl. D18—2)

To all whom it may concern:

Be it known that I, John E. Ryan, a citizen of the United States, residing at Danbury, in the county of Fairfield and State of Connecticut, have invented a new, original, and ornamental Design for a Tile Floor and Wall Covering, of which the following is a specification, reference being had to the accompanying drawing, forming part thereof.

The figure is a plan view of a tile floor and wall covering, showing my new design, the design being subject to such repetition of the portion shown as may be necessary to cover any given floor or wall area.

I claim:

The ornamental design for a tile floor and wall covering, as shown and described.

JOHN E. RYAN.
